UNITED STATES PATENT OFFICE.

LON McCaleb, OF DYERSBURG, TENNESSEE.

DRYING SUPPORT FOR ARTICLES.

Application filed March 4, 1922. Serial No. 541,162.

To all whom it may concern:

Be it known that I, LON McCaleb, a citizen of the United States, residing at Dyersburg, in the county of Dyer and State of Tennessee, have invented certain new and useful Improvements in Drying Supports for Articles, of which the following is a specification, reference being had to the accompanying drawings.

10 This invention relates to holders or hangers for drying small articles, such as handkerchiefs, dish cloths, etc., and the general object of the invention is to provide a device of this character particularly 15 adapted for holding napkins, dish cloths, etc., in contiguity to a hot water boiler or like source of heat.

A further object is to provide a very simple device of this character which is 20 made of a single length of wire, which may be readily put in place around the top part of the hot water tank or boiler, which may be readily removed, and which is particularly convenient and effective in actual practice.

25 My invention is illustrated in the accompanying drawings, wherein:—

Figure 1 is a fragmentary perspective view of a domestic boiler showing my device applied thereto;

Figure 2 is a fragmentary perspective view of one end of the device.

Referring to these drawings, it will be seen that my holder or support is, generally speaking, arcuate in form and provided with a plurality of hooks and adapted to partially surround the upper portion of a hot water boiler and be held in engagement therewith by a spring which extends 40 around the rear portion of the boiler.

In detail, my device is formed of a single length of wire which is arcuately bent to conform to the cylindrical shape of the boiler, this length 10 of wire at one end 45 being formed with an eye 11. The opposite end of the length of wire is bent to form an eye 12 and a coiled contractile spring 13 is permanently engaged with one of these eyes and detachably engaged with the other eye. The length of wire, after the eye 12 has been formed, is alternately bent to form 50 a plurality of hooks and then extended longitudinally along the wire 10. In detail, the wire, after the eye 12 has been 55 formed, is bent downward and outward, as at 14, then upward and coiled, as at 15,

then again downward, as at 16, and upward to the wire 10, then across and over the wire 10 at a very acute angle thereto, as at 17, and then again downward inside 60 of the wire 10, as at 14^a, and bent to form the bill of the next hook with the coil 15^a and so on, the last hook being formed adjacent the eye 11 and the shank of this last hook being extended upward to the wire 65 10 and then bent around the wire, as at 18, so as to clamp it securely in place.

It will be seen that by extending the portion 17 between the hooks over the top of the wire 10 that any weight disposed upon 70 the hook will be borne by the wire 10 as well as by the hook itself and that each hook is supported at two places on the wire. Thus weights disposed upon the hooks will not act to pull the hooks downward away 75 from the wire, this wire 10 constituting a body from which the hooks depend.

It will be seen that this device may be readily applied to the boiler A by simply unhooking one end of the spring 13, passing 80 it around the boiler, and again hooking it in the eye 11. The handkerchiefs, towels, dish cloths, napkins or other small articles which it is desired to dry may be hung upon these hooks, and hanging adjacent 85 the boiler receive heat therefrom and will readily dry. It will be seen that this device is very convenient, that it is simply made, and may be cheaply sold.

While I have illustrated details of construction, I do not wish to be limited thereto as it is obvious that these may be modified in many ways without departing from the spirit of the invention, though the particular construction which I have devised 90 is very simple and is thoroughly effective. Preferably that length of wire from which the hooks are formed will be clamped to the body wire at one or more points, as for instance at 19, by a wire wrapping or 95 sleeve.

I claim:—

1. A device of the character described formed of a single length of wire, the wire being bent to form an arcuate body having 100 eyes at its opposite ends, the wire then being extended beneath the body wire and bent to form depending hooks having upwardly turned bills, the portion of wire between said hooks extending over the top 105 of the body wire and normally resting thereon, and a coiled contractile spring permanent.

nently engaged at one end with one of said eyes and adapted to be detachably engaged with the other eye.

2. A device of the character described formed of a single length of wire, the wire being bent to form an arcuate body having eyes at its opposite ends, the wire being then extended beneath the body wire and

bent to form depending hooks having upwardly turned bills, the portion of the wire ¹⁰ between said hooks extending over the top of the body wire and normally resting thereon and being engaged therewith.

In testimony whereof I hereunto affix my signature.

LON McCaleb.
